(57) **CLAIM**

The ornamental design for a drywall sander, as shown and described.

DESCRIPTION

FIG. 1 is a perspective view of a first embodiment of a drywall sander showing our new design.

FIG. 2 is a left side elevational view thereof.

FIG. 3 a right side elevational view thereof.

FIG. 4 is a front elevational view thereof.

FIG. 5 is a rear elevational view thereof.

FIG. 6 is a top plan view thereof.

FIG. 7 is a bottom plan view thereof.

FIG. 8 is a perspective view of a second embodiment of a drywall sander showing our new design.

FIG. 9 is a left side elevational view thereof.

FIG. 10 is a right side elevational view thereof.

FIG. 11 is a front elevational view thereof.

FIG. 12 is a rear elevational view thereof.

FIG. 13 is a top plan view thereof.

FIG. 14 is a bottom plan view thereof.

FIG. 15 is a bottom perspective view thereof.

FIG. 16 is a bottom perspective view showing the view of the slot; and,

FIG. 17 is a bottom perspective view thereof.

The broken lines in the figures illustrate features that form no part of the claimed design.
